UNITED STATES PATENT OFFICE.

AUSTIN H. GLENN, OF DAHLGREN, ILLINOIS, ASSIGNOR OF TWO-THIRDS TO
H. V. SHARP AND ALPHONS AYDT, OF DAHLGREN, ILLINOIS.

INSTRUMENT FOR DETERMINING THE GAGE LEVEL AND ELEVATION OF RAILWAY-TRACKS.

SPECIFICATION forming part of Letters Patent No. 735,496, dated August 4, 1903.

Application filed April 1, 1903. Serial No. 150,657. (No model.)

To all whom it may concern:

Be it known that I, AUSTIN H. GLENN, a citizen of the United States, residing at Dahlgren, in the county of Hamilton and State of Illinois, 5 have invented a new and useful Instrument for Determining the Gage Level and Elevation of Railway-Tracks, of which the following is a specification.

This invention relates to implements employed for determining the level, gage, and elevation of railway-tracks, and has for its object to simplify and improve implements of this character and to increase their efficiency, extend their usefulness, and reduce their 15 weight without increasing the expense; and the invention consists in certain novel features of the construction, as hereinafter shown and described, and specified in the claims.

20 In the drawings illustrative of the invention, in which corresponding parts are denoted by like designating characters, Figure 1 is a side elevation, and Fig. 2 is a plan view, of the implement applied. Fig. 3 is a trans- 25 verse section on the line 3 3 of Fig. 1. Fig. 4 is a side elevation of the implement applied as a "leveler."

The improved device consists of a beam formed of spaced side members 10 11, connected by blocks and each provided with an intermediate depression terminating in shoulders 13 14, forming stops, said depressions being of a length to correspond to the "gage" of the railway-rails and adapted to be employed for that purpose, the rails indicated at 30 15 16. The members 10 11 are widened at one end by extensions 17 18 to increase the width in engagement with the rail 15 or 16, as the case may be, and thus increase the 35 steadiness of the device and prevent any tendency to be overturned when in use. At some intermediate point of the beam centrally thereof the inner surfaces of the members 10 11 will be recessed, forming shoulders 40 45 to provide supports for a plate 19, adapted to support a "fluid level-bulb" 20 of the ordinary form, the side members being cut away opposite the bulb, as shown at 21 22, to render the latter visible from both sides of the 50 implement. Above the bulb-recesses a combined handle and guard 23 is secured to the

side members, as shown, to enable the implement to be conveniently handled and transported, while at the same time affording protection to the fragile level-bulb. At the end 55 opposite the lugs 17 18 the side members 10 11 are extended, as at 24 25, and between these extended ends a scale 26 is movably supported by means of a longitudinal slot 27 in the scale engaging a transverse pin 28, passing 60 through the extended ends, as indicated. The scale will be supported adjustably between the extended ends by a set-screw 29, tapped through one of the end extensions 24 or 25. The scale member 26 is thus adapted to be 65 projected into engagement with one of the rails 15 or 16, as shown in Fig. 4, to determine the difference in height between the two rails and to provide a simply-operated and ready means for accurately determining the proper 70 relative positions of the rails upon curves. It will be obvious that by setting the one end of the implement upon the "high" rail and adjusting the scale until the bulb 20 is level the "reading" on the scale will denote the 75 exact difference of the height. When not required, the scale is foldable between the side members of the implement, as indicated by dotted lines in Fig. 1. By this simple means a very compact, complete, and convenient im- 80 plement is produced which may be employed to denote all the varying conditions of the railway-tracks and will enable the operators to readily correct any irregularities and re-store the track to its proper condition when 85 for any reason it becomes disarranged and likewise to properly adjust the relative positions of the rails when constructing new rail-ways.

The whole device will preferably be of 90 metal, generally "steel," except the level-bulb, and may be of any suitable strength or weight.

In the foregoing description is shown the preferred form of the implement, but is not 95 necessarily limited thereto, as modifications may be made therein without departing from the principle of the invention or sacrificing any of its advantages, and the right is therefore reserved of making all the changes which 100 may fairly come within the scope of the invention and the claims made therefor.

Having thus described my invention, what I claim is—

1. In a device of the class described, a beam formed of spaced side members each having an intermediate depression corresponding in length to the "gage" of the railroad and connected by transverse blocks at the extremities of said depressions, and with said side members laterally extended at one end and longitudinally extended at the other end, and a scale movably connected between said longitudinally-extended ends and capable of vertical adjustment relative to said beam, substantially as described.
- 15 2. In a device of the class described, a beam

formed of spaced side members having stops corresponding to the gage of the railway-tracks, and provided with oppositely-disposed recesses forming shoulders, a plate supported within said recesses on said shoulders, and a 20 level-bulb supported upon said plate, substantially as described.

In testimony that I claim the foregoing as my own I have hereto affixed my signature in the presence of two witnesses.

AUSTIN H. GLENN.
